UNITED STATES PATENT OFFICE.

WALTER B. BARKS, OF COLUMBUS, OHIO.

DESIGN FOR A NAME PLATE FOR RADIO SET.

Application filed February 6, 1926. Serial No. 16,434. Term of patent 3½ years.

To all whom it may concern:

Be it known that I, WALTER B. BARKS, a citizen of the United States, residing at Columbus, in the county of Franklin and State of Ohio, have invented a new, original, and ornamental Design for Name Plate for Radio Set, of which the following is a specification, reference being had to the accompanying drawing, forming a part thereof.

Figure 1 is a front view of the plate, showing my new design.

Figure 2 is a vertical central sectional view through the same.

It is understood that the portion on the right of the center line is a repetition of the portion shown on the left of the center line.

I claim:

The ornamental design for a name plate for radio set, as shown.

WALTER B. BARKS.
